UNITED STATES PATENT OFFICE.

EDWIN B. OLMSTED, OF DELEVAN, NEW YORK.

BALLOT DISTRIBUTING AND REGISTERING MACHINE.

SPECIFICATION forming part of Letters Patent No. 548,325, dated October 22, 1895.

Application filed February 23, 1895. Serial No. 539,448. (No model.)

To all whom it may concern:

Be it known that I, EDWIN B. OLMSTED, a citizen of the United States, residing at Delevan, in the county of Cattaraugus and State of New York, have invented certain new and useful Improvements in Voting - Machines; and I do hereby declare the following to be a full, clear, and exact description of the invention, such as will enable others skilled in the art to which it appertains to make and use the same.

This invention relates, generally, to voting-machines, and particularly to machines for delivering ballots to voters, and it has for its object to provide a durable and comparatively inexpensive machine adapted to deliver a ballot to a voter and at the same time register the delivery thereof, the mechanism constituting the machine being so arranged and constructed as to be set in motion by a weight dropped into the machine by the voter; and it consists of the parts and combinations of parts hereinafter fully described and claimed.

In the accompanying drawings, forming a part of this specification, Figure 1 is a vertical sectional view of my machine on the line $x-x$, Fig. 2; Fig. 2, a front elevation with the front end of the casing removed; Fig. 3, a vertical sectional view on the line $y-y$, Fig. 2; Fig. 4, a plan view of the machine with the top removed; Fig. 5, a detail perspective view of the tape-cutting device; Fig. 6, a detail front elevation of the tape-cutting device; and Fig. 7, a horizontal section on the line $z-z$, Fig. 2.

Similar numerals refer to similar parts throughout all the views.

Referring to the drawings, the numeral 1 represents the casing of my improved machine, which consists of a plain rectangular case or box having an end or rear door therein, within which the operative parts of my machine are arranged and secured in compact form, as will be described. At the rear end of the casing a bar 2 is arranged across the doorway and secured at each end to the side walls of the casing, and on this bar rests and is suitably secured the rear end of the envelope-receptacle 3, the forward or delivery end of said receptacle resting on and being firmly secured to the top edge of a partition

4, extending across the casing at a suitable distance from the front wall thereof to form a passage 5 therebetween, said passage being 55 preferably slightly flaring toward its lower end. The sides 6 of the envelope-receptacle also incline toward the delivery end thereof, and a strip 7 connects the upper part thereof. The forward ends are cut away, as 60 at 8, to form an irregular line, for a purpose to be hereinafter described.

To the forward ends of the sides 6 are secured narrow metal guide-plates 9, the front edges of which are cut away or formed to correspond to the shape of the end of the sides 6 of the envelope - receptacle and terminate in rounded forward projections 10, as clearly shown in Figs. 1 and 3.

At each side of the end of the envelope-receptacle at its bottom a rubber block 11 is inserted, so as to project slightly beyond the edge of said receptacle. To a vertical cleat 12, secured to the front side of the partition 4 within the passage 5, is horizontally-adjustably secured a metal plate 13 by means of screws passing through slots in the plate, and a similar plate 13 is secured in the same manner to the side wall of the casing. The plates 13 on their adjacent faces are formed with vertical grooves 14, which extend to a point on a line with the upper surface of the bottom of the receptacle 3, the groove being slightly flaring at its upper end, as at 15, Fig. 3, from which point the rear wall of the groove 85 is removed to the top of the plate and the remaining wall is formed with a rounded projection 16, extending over the line of the groove, as best shown in Fig. 3, and inwardly toward the plates 9 on the receptacle 3. The 90 plates 13 are secured in position slightly beyond the walls 6 of the receptacle and in front of the same.

To a cleat 18, secured to the side wall of the casing, is secured a square spout or chute 19, 95 having a rounded opening 20 in its front wall at the top, which corresponds with an opening 21 in the front wall of the casing. In the side walls of the spout or chute 19 are formed the grooves 22, in which the metal stirrup 23 100 of a metal platform 24 slides, said platform being provided with rubber or other pad 25 to deaden the noise made by the operating-ball, as will be described. To the center of the

bottom of the platform 24 is securely attached to the upper end of a metal bar 26, to the other end of which is rigidly secured the envelope-picker, which consists of a thin metal plate 27, as wide as the length of the envelopes to be operated upon, having at its lower edge a thin metal plate 28, the edge of which is formed with a slightly-inward curve at its center, as at 29, which is slightly sharpened, said plate 28 being secured to the plate 27 by hinges 30, as best shown in Fig. 2, whereby said plate 28 may swing thereon. At the lower edge of the plate 28 at each end is secured or formed a projecting pin 31, adapted to enter the grooves 14 of the metal plates 13, and which during the vertical movement of the picker travel through said grooves and cut-away portion of the plates 13, and are deflected out of a true vertical plane by contact in their downward stroke against the rounded projection 16 of said plates, thus turning or deflecting the swinging plate 28 inwardly against the cut-away ends of the sides of the envelope-receptacle and being deflected outwardly and into the grooves 14 when the pins 31 strike against the projections 10 of the guide-plates 9 on said receptacle, in which grooves the pins travel to the end of their stroke.

At the lower end of the spout or chute 19 at its rear side is formed an opening 32, similar to the opening 20 at its upper end, which opens onto the bottom of an inclined open chute or spout 33, secured to the side of said chute 19 and extending laterally or at right angles therefrom toward the side wall of the casing 1. The bottom of the chute 33 at its lower end terminates at a vertical chute 34, whose walls on three sides extend to the top of the sides of the chute 33, the wall next to said chute being cut away, so that an object falling from the end of the bottom of the chute 33 will drop into the chute 34. The chute 34 is formed with vertical grooves 35, in which slide the stirrups 36 of a ball-plate 37, similar to platform 24, said stirrups being connected by a cord or chain 38, which passes over wheels 39, which are journaled in bearings between the short bars 40, arranged diagonally across one corner of the casing 50 above said chutes. One end of the cord or chain 39 is connected directly to the stirrup 23 and its other end to a rod 41, attached to stirrups 36, on which is secured a counter-balancing-weight 42 to equalize the platforms, one of which being heavier than the other owing to the addition of the weight of the picker-plate thereto. At the lower end of chute 34 an opening 43 is formed, which communicates with a similar opening 44, formed in the side wall of the casing of the machine, both openings being indicated by dotted lines in Fig. 2.

In the rear wall of the chute 34 a slot 45 is formed, which is in line with the groove 35, into which the end of the long arm of a lever 46 normally projects, said lever being pivoted in ears or lugs 47, secured to the rear

wall of said chute, whereby the stirrup 36 in its downward movement will strike against and swing outwardly the end of the arm. 70 The short arm 48 of the lever 46 is bent rearwardly and formed with a counterbalance 49 to return and hold the long arm in its normal position in the slot and in the path of the stirrup. To perforated ears 50 on the short arm of the lever is pivotally attached one end of a pawl 51.

The pawl 51 extends to and engages a ratchet-wheel 52, mounted on a shaft 53, having its bearings in a bracket 54, secured to the under side of the bar 2, on which shaft, alongside said wheel 52, is mounted a friction-disk 55, of rubber or other suitable material. A suitable stop, as 56, attached to bar 2 limits the throw of the pawl. At a suitable distance below the shaft 53 a table or platform 57 is suitably supported, in the upper surface of which is formed a T-shaped groove 58, adapted to receive a similar-shaped tongue 59, formed on the bottom of a block 60, to the front end of which is hinged the paper-tape guide and cutting device, as shown in Figs. 1 and 6. This device consists of a block 61, the front end of which is hinged to block 60, so as to rest on the free end of a curved flat spring 62, the opposite end of which is secured to said block 60. The upper part of the block 61 is channeled its entire length, as at 63, the front end of said channel being curved or rounded off on a long curve, as at 64, and its rear end being formed with a sharper curve, as at 65, and being covered by a curved plate 66, attached to the walls of the channel and extending at one side beyond the same, thus forming a curved passage at 67 the rear end of the channel.

To the bottom of the block 61 is attached a metal plate 67, so as to leave a space between said plate and the under surface of said block, in which space a knife-blade 68 is arranged, one end of which is pivoted between the extended end of the curved plate 66, which is provided with a lug for this purpose, and the extended end of plate 67, the other end of said knife-blade extending outwardly to form a handle, whereby a shear cut may be made between said blade and the lower edge of the curved plate 66. The disk 55 rests in yielding contact with the bottom of the channel 63, and when operated tends to feed the paper tape 69, which extends through said channel from a paper-carrying spool 70, mounted in a suitable bracket 71, secured to the bottom of the casing 1 by a T-joint 72, whereby the bracket may be removed to renew the tape when necessary.

The door 73 is provided with a suitable lock, preferably of a combination type, and a spring-metal slightly-curved plate 74 is secured to the edge thereof and projects inwardly therefrom, on which is formed a projection 75, having an inclining outer face and a front face, as at 76, which inclines slightly toward its lower end. This plate 74 is arranged on the

door in line with the knife-blade 68, and when the same is thrown out, as shown in Fig. 1, the handle of the same, which is curved, as shown, is in position to be struck by the door in the 5 act of closing the same and turned inward, the end of the spring-plate 74 passing the end of the handle, and when the door is fully closed the projection 75 lies behind the end of the handle in position to throw the blade 10 out when the door is opened. In moving the blade out the same is kept up close against the lower edge of the curved plate 66, owing to the inclined face of the projection 75 bearing thereagainst and tending to raise said 15 blade, whereby a clean, sharp, shear cut will be made through the paper tape lying in and projecting from the curved passage between the plate 66 and the bottom of the channel 63 in block 61.

20 To the inner face of the end wall of the casting 1 I secure a tapering block 77 vertically in position immediately in front of the discharge end of the envelope-receptacle, the lower end of said block being beveled, as 25 shown, and at each side of said block I secure one end of a flat curved spring 78, the free ends of which are in contact with and press the picker-plates 27 and 28 inwardly, so as to hold the same against the envelopes 79 in the 30 receptacle at all times, both during the movement of the picker and when it is at rest.

A pusher 80, consisting of a triangular-shaped trough carrying a weight 81, is placed in the receptacle in rear of the envelopes and 35 bearing or resting thereagainst, which follows the envelopes down the inclined bottom of the receptacle and holds the same in their upright position.

The operating-ball is shown in dotted lines 40 in Figs. 1 and 3, and is of sufficient weight to lower platform 24 and thus raise the platform 37 when it is dropped through the opening 21 onto platform 24.

The paper tape 69 has printed thereon a 45 series of numbers, beginning at zero or cipher, which are spaced a suitable distance apart, and which correspond to or exceed the number of voters who have been registered in the particular voting district in which the machine is to be used. The tape, wound on a 50 spool, is then arranged in the bracket-bearing 71 and the end thereof led up to and over the table 61 through the channel therein and carried back to and under the curved plate 55 65, leaving the tape in such position that the first movement of the disk or roller 55 will move the tape backwardly till its first number "1," printed thereon, will be carried past the knife-blade 68, and bringing the next 60 number "2" in position to be moved a like distance by the next movement of disk or roller 55. A number of ballots corresponding to the number of registered voters are folded and placed in envelopes, and the envelopes 65 turned upside down and with their backs forward are arranged upright in the envelope-case 3 and the weighted pusher 80 placed be-

hind them, so as to retain them in their upright position and to press them forward.

In order to set the mechanism in motion, 70 the ball is dropped through the opening 21 in the front wall of the case and onto platform 24, thus causing the latter to descend in chute 19 and through the cord or chain 38 raising the platform 37 in chute 34 till its upper surface is in line with the bottom of chute 33. When the platform reaches the end of the stroke, the ball rolls off the platform 24 and through the opening 32 in the wall of chute 19 and into chute 33, down which it rolls and 80 onto the platform 37, which it causes to descend in chute 34 and off of which it rolls through an opening 43 in the chute and out through an opening 44 in the side wall of the case. During the descent of platform 24 the 85 swinging plate 28 of the picker is deflected out of a vertical plane, as hereinbefore described, and caused to engage the flap of the envelope at the delivery end of the envelope-receptacle, when the pins 31 at the ends of 90 said plate, striking against the projections 10 on the guide-plates 9, deflect the swinging plate 28 outward, which carries the envelope with it and past the rubber blocks 11, which serve to prevent the escape of the next envelope with the one engaged by the plate. The outward movement given the plate causes its pins to be brought in line with the grooves 14 in plates 13, in which they travel for the balance of the downward stroke of the picker. 100 The envelope-flap is held against the plate by the block 77 till the free edge of the flap passes the end of the block, when it flies out beyond the block and is prevented thereby being carried up by the picker on its upper 105 stroke should it through any cause have a tendency to adhere to the picker. The envelopes drop off the picker and are removed through an opening in the front or bottom, if preferred, of the case. 110

During the downward movement of platform 37 it strikes against and throws outwardly the long arm of lever 46, which normally lies in the slot 45 of chute 34, thus causing the pawl 51 to impart a partial revolution 115 to the ratchet-wheel 52, and consequently to the roller or disk 55, thereby moving the tape 69 backwardly at each complete stroke of the picker-plate a predetermined distance.

After the poll has closed the officers in 120 charge open the door 73 of the case, causing the projection 75 on the spring-plate 74, attached to said door, to engage the handle of knife-blade 68 and swing the same out with the door, thus cutting off the projecting portion of the tape 69, the last number on such severed portion showing the number of complete movements of the picker, and consequently the number of ballots delivered to 125 voters, which should correspond to the number found in the ballot-boxes.

There should be one complete machine for each political party set up in the booth where the voting takes place, and a guard stands

outside of the same and delivers to each voter a weight-ball as he enters the booth, and when he drops the same in the case of the party for which he intends to vote an envelope containing a ballot of that party is delivered to him and the ball passing through the machine rolls back through a suitable spout or other conduit connected to all the machines to the guard.

10. Having thus described my invention, what I claim as new, and desire to secure by Letters Patent, is—
1. The combination, in a voting machine of an envelope receptacle, mechanism for positively engaging and removing an envelope from said receptacle, and a weight for imparting a vertical reciprocation to said mechanism, substantially as described.
  2. The combination, in a voting machine, of an envelope receptacle, means for feeding the envelopes in an upright position from end to end of said receptacle, and means adapted to be reciprocated by a weight for positively engaging and automatically removing the envelopes, one at a time, from the front end of said receptacle, substantially as described.
  3. The combination, in a voting machine, of an envelope receptacle adapted to hold envelopes in an upright position, means for pressing the envelopes toward the discharge end of said receptacle, a picker for removing envelopes, one at a time, from the discharge end of said receptacle, and a free weight whose passage through the machine imparts a vertical reciprocation to said picker, substantially as described.
  4. The combination, in a voting machine, of an envelope receptacle adapted to hold envelopes in an upright position therein, a gravity actuated pusher for pressing the envelopes toward the discharge end of the receptacle, means for preventing the accidental discharge of the envelopes, a vertical reciprocating picker for removing the envelopes, one at a time, from the discharge end of said receptacle, and means, actuated by the picker actuating-mechanism, for registering the number of envelopes removed, substantially as described.
  5. The combination, in a voting machine, of an envelope receptacle adapted to hold envelopes in an upright position, therein, a pusher for pressing the envelopes toward the discharge end of the receptacle, a vertically movable picker for engaging the flaps of said envelopes one at a time, to remove them from the receptacle, a platform connected to said picker, a weight for imparting a vertical reciprocation to picker and platform, and means for directing the picker in its vertical movement, substantially as described.
  6. The combination, in a voting machine, of an envelope receptacle adapted to hold envelopes therein in an upright position, a vertically reciprocating picker having a swinging plate forming its lower edge for engaging the flaps of said envelopes to remove the same,

one at a time, from said receptacle, means for holding the picker against the envelopes, means for holding the flaps against said swinging gate, and means for deflecting the picker out of a true perpendicular line in its reciprocation with the picker, substantially as described.

7. The combination, in a voting machine, of an envelope receptacle adapted to hold envelopes therein in an upright position, a movable platform, a picker secured to said platform adapted to remove the envelopes one at a time, from said receptacle, a counter-balancing platform connected to the picker-platform adapted to remove the envelopes one at a time, from said receptacle, a counter-balancing platform connected to the picker-platform, and a loose weight adapted to move the picker-platform downwardly its full stroke and then to depress or lower the counter-balancing platform, whereby the picker platform is raised to its normal position, substantially as described.

8. The combination, in a voting machine, of an envelope receptacle adapted to hold envelopes therein in an upright position, a movable platform, a picker having a swinging plate forming its lower edge rigidly attached to said platform, a counterbalancing platform, a chain connecting said platform, a loose weight for moving the picker-platform its full stroke and for causing the counter-balancing platform to descend at the end of the stroke of the picker-platform to return the latter to its normal position, and means, operated by the descending counterbalancing platform, to register the number of envelopes removed, substantially as described.

9. The combination, in a voting machine of an envelope receptacle adapted to hold envelopes in an upright position therein, friction pads arranged at the discharge end of said receptacle, a guide plate attached to each side of said discharge end, grooved guide bars arranged adjacent to and in front of said guide plates, a picker having a swinging plate forming its lower edge, pins secured at each side of said edge, means for imparting a vertical reciprocation to said picker, and means for holding said picker against the discharge end of said envelope receptacle, substantially as described.

10. The combination, in a voting machine, of an envelope receptacle adapted to hold envelopes therein in an upright position, a reciprocating picker for removing the envelopes, one at a time, from said receptacle, means for guiding the picker in its movements, a vertically movable counterbalancing platform connected to said picker, a pivoted lever having its long arm projected into the path of said platform, and having a weighted short arm, a pawl pivotally connected to said short arm, a shaft, a ratchet wheel mounted thereon, a friction disk arranged on said shaft, a tape supporting block held in yielding contact with said disk, and a paper tape holding spool, substantially as described.

11. The combination, in a voting machine, with an envelope receptacle, a picker for re-

moving the envelopes, one at a time, from said receptacle, and means for automatically reciprocating said picker, of a device for registering the number of envelopes removed by the picker, said device being operated by the means which operate the picker mechanism, substantially as described.

12. The combination, in a voting machine, with an envelope receptacle, a picker for removing the envelopes therefrom, one at a time, and means for imparting a vertical reciprocation to said picker, of a registering device, consisting of a pivoted lever having a long arm and a weighted short arm, a pawl 15 loosely connected to said short arm, a stop for limiting the throw of the pawl, a shaft, a ratchet wheel, mounted thereon, a friction disk on said shaft alongside of said ratchet wheel, a channeled block held in yielding 20 contact with said disk, a paper tape extending through the channel, and a removable spool for holding said paper tape, substantially as described.

13. The combination, in a voting machine, 25 with an envelope receptacle, a picker for removing envelopes, one at a time, therefrom, and means for imparting a vertical reciprocation to said picker, of a registering device connected to the means for reciprocating the 30 picker, and comprising a paper tape wound on a spool, and means for feeding or unwinding said tape off its spool a predetermined distance at each reciprocation of the picker, substantially as described.

14. The combination, in a voting machine, 35 with an envelope receptacle, a picker for removing the envelopes, one at a time, therefrom, and means for imparting a vertical reciprocation to said picker, of a device actuated by the picker actuating mechanism for registering the number of envelopes removed by the picker, comprising a paper tape wound on a spool, means for unwinding the same a predetermined distance at each reciprocation 40 of the picker, and a knife blade adapted to automatically cut off the projecting end of

said tape when the door of the casing of the machine is opened, substantially as described.

15. The combination, in a voting machine, 50 with an envelope receptacle adapted to hold envelopes upright therein, a picker for removing the envelopes, one at a time, therefrom, and means for imparting a vertical reciprocation to said picker, of a device, actuated by the picker actuating mechanism, for registering 55 the number of envelopes removed, said device comprising a paper tape wound on a spool, a friction disk for unwinding the tape a predetermined distance at each reciprocation of the picker, a curved plate, a knife blade pivotally 60 secured to said plate, and means connecting the blade and the door of the casing of the machine, whereby the tape will be severed instantly upon opening the door, substantially 65 as described.

16. The combination, in a voting machine, 70 of a casing having a door, a spring metal plate having a projection thereon secured at one end to said door, an envelope receptacle, a picker for removing the envelopes, one at a time, therefrom, means for vertically reciprocating said picker, a device, actuated by the picker actuating mechanism, for registering the number of envelopes removed by the picker, said device comprising a paper tape 75 wound on a spool, means for unwinding said tape a predetermined distance at each reciprocation of the picker, and a knife blade pivotally attached to the tape unwinding device, whereby the spring plate attached to the door 80 may swing the free end of said knife outwardly to sever the projecting end of the tape, when the door is opened, and moving it into position to be swung inwardly when the door is closed, substantially as described. 85

In testimony whereof I affix my signature in presence of two witnesses.

EDWIN B. OLMSTED.
